UNITED STATES PATENT OFFICE.

FRANK W. ROBINSON, OF READING, PENNSYLVANIA, ASSIGNOR TO THE NOLTE & HORST CO., OF READING, PENNSYLVANIA, A CORPORATION OF PENNSYLVANIA.

PLATING ATTACHMENT FOR CIRCULAR-KNITTING MACHINES.

1,203,132.

Specification of Letters Patent. Patented Oct. 31, 1916.

Application filed March 28, 1916. Serial No. 87,149.

To all whom it may concern:

Be it known that I, FRANK W. ROBINSON, a citizen of the United States, residing at Reading, in the county of Berks and State of Pennsylvania, have invented certain new and useful Improvements in Plating Attachments for Circular-Knitting Machines, of which the following is a specification.

My invention relates to plating attachments for circular knitting machines in which striping-thread carrier fingers are employed each of which has a universal-joint mounting, and a needle-engaging swing, as shown in Patent No. 1,077,304, issued to me Nov. 4, 1913, and in my pending application Serial No. 866,579, filed Oct. 14, 1914.

The present improvement consists in providing means for intermittently operating said fingers in a plurality of series, during the knitting operation, so as to produce broken stripes having the breaks relatively positioned as required for predetermined embroidery effects; as fully described in connection with the accompanying drawings and particularly defined in the claims.

Figure 1 is a sectional elevation indicating a circular knitting machine having my invention applied thereto in connection with a controlling pattern mechanism. Fig. 2 is a plan view on the line 2--2 of Fig. 1 showing the arrangement of the carrier fingers in different series for selective operation; the cams for imparting needle-engaging swing thereto being shown as withdrawn to inoperative position. Fig. 3 indicates a stocking having polka-dot plating adapted to be produced by the specific construction shown. Fig. 4 is a detail view of the pattern-operated star wheel employed.

The drawings indicate a knitting machine having a non-rotary needle cylinder 1 mounted on a frame 2, the usual rotary cam ring and other well known knitting mechanism not involved in the application of my improvements being employed. The striping-thread carrier fingers 4 are similar in general construction and mounting to those shown and described in my prior patent and application referred to, each having a universal-joint mounting 5 at the periphery of a sleeve 6, fixed to a central carrier rod 7 above the needle cylinder, and a rigidly projecting portion or arm 8 through which a needle-engaging swing is imparted to it.

As in my previous construction referred

to, the rigid arm 8 of each carrier finger is arranged to serve as a rocker-arm, through which a needle-engaging swing is imparted to the finger by a contacting cam; this being effected by successive actions of the cam upon an outer portion 10, and a lateral or crank-arm portion 11, of the rocker-arm. In my present improved construction a number of these carrier fingers (nine as shown) are arranged in a circular series around the central carrier rod 7, and these are divided into separately-operative sub-series by providing them with cam-contacting portions arranged at different distances from the knitting axis so as to lie in one or another determined cam-path; those fingers which have cam-contacting portions arranged in a given path being thus grouped together for selective operation, as determined by a pattern-controlled cam mechanism.

As shown in Fig. 2 each of the rocker-arms 8 is provided with two cam-contacting rollers through which radial and lateral swings respectively are imparted to the finger; said rollers having collars, *aa*, *bb*, *cc*, or *dd* forming the cam-contacting portions above referred to as being located in different cam-paths. The collars *aa* of determined fingers are all at one distance from the center of rotation, the collars *bb* at another distance, the collars *cc* at a third distance, and the collars *dd* at a fourth distance.

The cam mechanism shown for selectively operating determined fingers as thus grouped in different series, comprises two similar cams 15, 15 each formed at one end of a rigid carrier rod 16; the other end of said carrier rod resting upon a pattern-adjusted support 17 or 18 adapted to raise or lower the cam to operative or inoperative position. These cams are also adjustable into different paths as required for operating upon cam-contacting collars *a*, *a*, *b*, *b*, *c*, *c*, or *d*, *d*, as desired. This is accomplished as shown by merely providing a single adjustable cam guide 20 having tapered passage-ways 21, 21 in which said cam rods are movable longitudinally in any position of the guide; and the latter being adjustably set in a fixed support 22, as determined by a series of notches 24, so as to hold the cams in the desired paths. The cam rods are similarly guided in a fixed bracket 25 adjacent the pattern-adjusted supports 17, 18. These adjustable cam supports 17, 18, as

shown, are oppositely eccentric portions on a shaft 30 suitably mounted on the cam cylinder 3, and periodic rotary motion is imparted to said shaft in well known manner, 5 through a star-wheel 31 thereon arranged to contact with a pin 32 when the latter is projected by action of pattern chain 33, so that the respective cams will be automatically lowered or raised at determined times 10 as required.

As shown in Fig. 1 the cam rods are held in slightly inclined positions, to position the cams for the inner paths *aa* and *bb* respectively (see Fig. 2); but as they are moved 15 outward by the adjustable guide 20, they assume a more vertical position upon the adjustable supports 17, 18, thereby slightly raising the cams when they are set into the outer paths *cc*, *dd* and securing a uniform 20 swing of the fingers without varying the size of the cam-contacting collars *a b c d*. The adjustment of the cams jointly into different paths, by a single guide 20 and by hand, as indicated, is ordinarily preferable, 25 the pattern-controlled lowering and raising of the cams provided for, effecting accurately and automatically the constantly recurring changes required.

The operation of my improved mechanism 30 will be understood by briefly describing the production of a stocking having staggered polka-dot ornamentation as indicated in Fig. 3.

The stocking is knit in the usual manner 35 to the point at which the polka-dot plating is to appear. At this point the cams 15, 15 are set by the guide 20 directly beneath the contact collars *a a* and *b b*. The pattern chain 33, is rotated through the eccentric- 40 operated pawl 35, mounted on the main shaft 36 of the machine and acting upon the ratchet-toothed wheel 37 secured to the pattern wheel shaft 38; and one end of a lever 41 is arranged to fall into notches 39, 40, so 45 that the other end will operate a bell crank 43 which normally holds the pin 32 out of engagement with the star wheel 31. When the lever 41 is actuated by a notch 29 in the pattern wheel 33, the star wheel is rotated by 50 pin 32 so as to raise one cam 15 into operative position for the fingers in its path. As shown in Fig. 1, support 18 is raised with 55 the corresponding cam 15, lying in the path of the contact collars *a a*, so that only the alternate carrier fingers 4 having said collars will be operated (Fig. 2). The pattern chain determines the length of the polka-dots; and after a determined interval of plain knitting the other support 17 and cam 60 15 are raised by a further movement of the star wheel, so as to be operative upon the contact collars *bb* in a different path, the effect being to form the spaced polka-dots in intermediate longitudinal lines. This 65 alternate placing of the polka-dots is con-

tinued until the heel of the stocking is reached, when the cams 15, 15 are moved by operation of the guide 20, to the inoperative position indicated in Fig. 2. After the completion of the heel, the dots are continued 70 upon the upper part of the foot, but not on the lower half; the additional contact collars *cc dd* being provided only upon the fingers which engage the needles knitting the top half of the foot, and the cams 15, 15 being 75 now moved by guide 20 so as to operate only upon these collars *cc* and *dd*. The pattern chain then operates the star wheel 31 to cause the polka-dots to appear only upon the upper half of the foot in the same manner as 80 when the cams were actuating all the fingers for the leg portion of the stocking. The pattern chain indicated is arranged to make polka-dots embracing four courses at intervals of about thirty courses, in staggered relation, but this particular arrangement may be readily varied as desired. The attachment does not interfere with the ordinary operation of the machine and when the cams are in the position shown in Fig. 2, the machine may be used for continuous plain knitting as usual.

What I claim is:

1. In combination with a circular knitting machine, a plating attachment comprising striping-thread carrier fingers each having a universal joint mounting and arranged in a plurality of separately operatable series, and means for imparting a needle-engaging swing to different determined series in different determined knitting courses.

2. In combination with a circular knitting machine, a plating attachment comprising striping-thread carrier fingers each having a universal joint mounting and arranged in a plurality of separately operatable series, and means for imparting a needle-engaging swing to different determined series in different uniformly-separated knitting courses.

3. In combination with a circular knitting machine, a plating attachment comprising striping-thread carrier fingers each having a universal joint mounting and arranged in a plurality of separately operatable series, and means for imparting a needle-engaging swing to one of said series in determined courses and to another of said series in other determined courses.

4. In combination with a circular knitting machine, a plating attachment comprising striping-thread carrier fingers each having a universal joint mounting and arranged in a plurality of separately operatable series, and means for imparting a needle engaging swing to one of said series in determined courses and to another of said series in other determined courses with a uniform spacing apart of said determined courses in different longitudinal lines.

5. In combination with a circular knitting

machine, a plating attachment comprising striping-thread carrier fingers each having a universal joint mounting and arranged in a plurality of separately operatable series, 5 and means for imparting a needle engaging swing to a determined series in determined successive courses and to a different series in other successive courses.

6. A plating attachment for circular knitting machines comprising a circular series 10 of striping-thread carrier fingers each of which is provided with a universal-joint mounting and with a rigidly projecting cam-operated rocker-arm, the cam-contacting 15 portions of different rocker-arms being located in different cam-paths; a plurality of operating cams; and means for adjusting said cams into and out of operative position relative to the differently located cam-contacting 20 portions of said rocker-arms.

7. A plating attachment for circular knitting machines comprising a circular series 25 of striping-thread carrier fingers each of which is provided with a universal-joint mounting and with a rigidly projecting cam-operated rocker-arm, the cam-contacting 30 portions of different rocker-arms being located in different cam-paths; a plurality of operating cams; and means for jointly adjusting said cams into determined cam-paths and for separately adjusting the same

into and out of operative positions relative to said cam-contacting portions.

8. A plating attachment for circular knitting machines comprising a circular series 35 of striping-thread carrier fingers each of which is provided with a universal-joint mounting and with a rigidly projecting cam-operated rocker-arm, the cam-contacting portions of different rocker-arms being 40 located in different cam-paths; an operating cam for said rocker-arms having a rigid carrier rod, pattern-operated means for adjusting said cam rod longitudinally, and separate means for adjusting the cam into 45 one or another determined path.

9. A plating attachment for circular knitting machines comprising a circular series of striping-thread carrier fingers each of which is provided with a universal-joint mounting 50 and with a rigidly projecting cam-operated rocker-arm, the cam-contacting portions of different rocker-arms being located in different cam-paths; a plurality of operating cams for said rocker-arms each having a 55 rigid carrier rod, pattern-operated means for adjusting said cam rods longitudinally, and separate means for jointly adjusting the cams into different paths.

In testimony whereof I affix my signature. 60

FRANK W. ROBINSON.
